UNITED STATES PATENT OFFICE.

CHRIST SCHAUM AND RAYMOND H. WILLIAMS, OF KULPMONT, PENNSYLVANIA.

PROTECTIVE HOLDER FOR BOTTLES.

1,196,592.

Specification of Letters Patent. Patented Aug. 29, 1916.

Application filed October 30, 1915. Serial No. 58,867.

To all whom it may concern:

Be it known that we, CHRIST SCHAUM and RAYMOND H. WILLIAMS, citizens of the United States, residing at Kulpmont, in the county of Northumberland and State of Pennsylvania, have invented new and useful Improvements in Protective Holders for Bottles, of which the following is a specification.

- 10 The present invention relates to protective holders for milk or similar bottles, one of the objects being to provide an extremely simple, cheap, ornamental and reliable device of this character which may be attached 15 to a door or casing and which is provided with an aperture whereby the neck of the bottle may be arranged within the casing and locked thereto by the deliverer, but wherein the locking element is so arranged 20 as to prevent the operation thereof from the exterior of the building, so that the bottle can only be removed from the casing when the door is swung to its open position.

Another object of the invention is to provide a device of this character having an indicator arranged thereon, whereby the dispenser of the bottle may readily ascertain the quantity of milk, or the like, required.

A further object of the invention is to provide a device of this character which will accommodate itself to bottles having various sizes of necks.

With the above and other objects in view, the improvement resides in the construction, combination and arrangement of parts set forth in the following specification and falling within the scope of the appended claims.

In the drawings: Figure 1 is a perspective view illustrating the application of the improvement, Fig. 2 is a central horizontal sectional view through the same, Fig. 3 is a sectional view approximately on the line 3—3 of Fig. 2, and Fig. 4 is a perspective view looking toward the inside of the casing.

45 In the drawing 1 designates a stationary member, such as the casing of a door, 2 the swinging member which is hingedly secured to one side of the casing and which is contacted, at its free end, by a shoulder formed 50 by rabbeting the casing in the usual manner.

The numeral 3 designates a housing or casing which has two of its sides open, one of the said open sides having its edges flanged 55 outwardly and provided with apertures for the reception of securing elements whereby

the casing 3 may be secured to either the swinging or the stationary member. For the sake of compactness as well as to add to the ornamentality of the device the casing 60 has its closed side rounded, as at 4, while its top is provided with a sight opening below which is pivotally secured, as at 5, a disk 6, the said disk being provided adjacent its periphery with a plurality of indicating 65 marks 7 which are adapted to be disclosed through the opening when the disk is revolved upon its pivot. If desired suitable means may be provided for retaining the disk against rotation, and the indicating 70 characters upon the said disk indicate the quantity of milk to be delivered by the milkman. Preferably the upper face of the casing is inclined from its flanged edge, so that the same will shed moisture, while the lower 75 face 8 is horizontally straight. This face 8 is centrally provided with a round aperture 9 of an area sufficient to receive the necks of various sizes of milk or other bottles. Pivotally secured, as at 10, to the inner face of the 80 bottom of the casing is a curved plate 11, the pivot of the said plate being preferably arranged at the open and flanged side of the casing adjacent the edge of the aperture 9. The flat curved plate 11 has its free end provided 85 with a depending knob 12 which passes through an elongated slot 13 in the said lower face of the casing, and this knob is adapted to serve as a means whereby the curved plate may be swung upon its pivot to 90 bring the inner periphery of the same within the aperture 9, so as to engage with the neck of the milk bottle below the bead formed at the mouth thereof. The free end of the curved plate 11 is provided with a 95 spring catch 15, the same being adapted to co-act with the teeth of the rack bar 14 and so lock the plate in an adjusted position to grasp the necks of bottles of various sizes. The spring catch is provided with a finger 100 16, whereby the same may be brought out of engagement with the rack bar and the plate swung rearwardly upon its pivot to permit of the removal of the milk bottle from the casing. It will, of course, be understood 105 that the spring catch cannot be operated from the outside of a building and the same is so arranged that the slot 13 is fully covered by the curved plate 11, so that an instrument cannot be inserted through the slot 110 to withdraw the catch from its engagement with the rack bar.

From the above description, taken in connection with the accompanying drawings, the simplicity of the device, as well as the advantages thereof will, it is thought, be 5 perfectly apparent to those skilled in the art to which such invention appertains without further detailed description.

Having thus described the invention, what we claim is:

- 10 1. In a milk bottle holder, a casing adapted to be secured to a support and having an open side which is adapted to be closed by a member movable with relation to the support, said casing having its underface 15 provided with an aperture, a curved plate pivoted in the said casing adjacent the said aperture, means connected with the plate and extending below the bottom of the casing for swinging the plate to bring the same 20 within the area of the aperture, means for locking the plate in such position, said means being operable to release the plate when the movable member is brought away from the support.
- 25 2. In a milk bottle holder, a casing having open sides, one of which is flanged and

adapted to be secured to either a stationary or hinged member whereby the second open end will be normally closed by the other member, when the hinged member is 30 swung closed upon the stationary member, the outer side of the casing being round, the top of the casing being inclined from its flanged side to its said rounded side, an indicator upon the said top and operated from 35 the interior of the casing, the bottom of the casing having an aperture, a flat curved plate pivoted within the said bottom, a spring catch upon the free end of the plate, a rack bar within the casing adapted to be 40 engaged by the plate and operative from the exterior of the casing to swing the plate to bring the same within the area of the aperture, and a finger member upon the catch, as and for the purpose set forth.

In testimony whereof we affix our signatures in presence of two witnesses.

CHRIST SCHAUM.

RAYMOND H. WILLIAMS.
